UNITED STATES PATENT OFFICE.

NORRIS E. GOODRICH, OF BATTLE CREEK, MICHIGAN, ASSIGNOR TO SANITARIUM EQUIPMENT COMPANY, OF BATTLE CREEK, MICHIGAN.

DESIGN FOR A CABINET.

Application filed March 27, 1929. Serial No. 30,632. Term of patent 14 years.

To all whom it may concern:

Be it known that I, NORRIS E. GOODRICH, a citizen of the United States, residing at Battle Creek, in the county of Calhoun and State of Michigan, have invented a new, original, and ornamental Design for Cabinet, of which the following is a specification, reference being had to the accompanying drawing, forming part thereof.

The figure is a front perspective view of a cabinet, showing my new design.

I claim:

The ornamental design for a cabinet, as shown.

NORRIS E. GOODRICH.
